His Attorney.

UNITED STATES PATENT OFFICE.

CHARLES C. ABBOTT, OF PITTSFIELD, MASSACHUSETTS, ASSIGNOR TO GENERAL ELECTRIC COMPANY, A CORPORATION OF NEW YORK.

HEATING UNIT.

Application filed May 5, 1919. Serial No. 294,837.

To all whom it may concern:

Be it known that I, CHARLES C. ABBOTT, a citizen of the United States, residing at Pittsfield, county of Berkshire, State of Massachusetts, have invented certain new and useful Improvements in Heating Units, of which the following is a specification.

My invention relates to electric heating units and more especially to heating units 10 of the type in which a resistance conductor is wound upon a core of insulating material and which may be inclosed in a metallic sheath and insulated from it by a thin dense layer of insulating material, and has for its 15 object the improvement in a device of this character.

This unit is well adapted for use with machines subject to considerable vibration, such as shoe making machines. The main 20 difficulty heretofore has been to get a heating unit that could withstand the vibrations, since the core which is the heaviest element in the unit, on becoming slightly loose may pound itself against the insulated sides 25 in closing the core, and short-circuit the resistance conductor on the metallic sheath. One of the objects of my invention is to provide a heating unit that will overcome this difficulty. Another object of my invention 30 is to provide a simple, efficient and economical terminal connection. Further objects and purposes of my invention will appear in the course of the following specification, in which I have shown my invention embodied in concrete form for the purpose of 35 illustration.

My invention will best be understood by reference to the accompanying drawings in which Fig. 1 is a longitudinal section, partly 40 in elevation, of one form of heating unit embodying my invention. Fig. 2 is an end view thereof and Fig. 3 is a detail sectional view thereof showing the manner in which the heating element is secured to the terminals.

Referring to the drawings, 1 is a core of insulating material, preferably of lava, in which two holes, 2 and 3, have been drilled lengthwise to accommodate the terminals 45 4 and 5 respectively. The hole 2 extends part way into the core, whereas the hole 3 extends clear through the core as shown. Two holes 6 and 7 are drilled radially into the core, one being at each end thereof, con-

nected with the holes 2 and 3 respectively 55 and extending beyond the latter holes as shown at 8 and 9 in Fig. 1. Each of the terminals 4 and 5 is provided with a hole 10 and 11 respectively extending through said terminals and a groove 12 and 13 respectively around the terminals near each of the holes 10 and 11. It will be observed that the holes 10 and 11 through the terminals and the grooves thereon coincide with the holes 6 and 7 of the core, respectively, 60 as shown in Fig. 1. A resistance conductor 14 is wound about the core 1, and secured at its ends to the terminals 4 and 5 respectively in the manner hereinafter described. A metal sheath 15 screw threaded on its inside at each end incloses the core 1, with an intervening layer of refractory insulating powder 16, such as magnesia insulating the resistance conductor from the sheath. The sheath is closed at one end by insulating washers, preferably mica washers 17, 75 which are provided with holes 18 and 19, through which the terminals 4 and 5 project respectively, which washers are held in place by a ring 20, screw threaded on its outside 80 to engage the threads of the sheath. At its opposite end the sheath is closed by a disc or member 21 which is screwed into the sheath.

In the manufacture of a heating unit in 85 accordance with my invention, holes 2 and 3 are drilled lengthwise in the core 1, and the terminals 4 and 5 are inserted in the holes 2 and 3 respectively so that the holes and grooves of said terminals coincide with 90 the radial holes 6 and 7 respectively. One end of the resistance conductor 14 is then inserted in holes 6, through hole 10 of the terminal 4, to the bottom of hole 6 at 8. The terminal 4 is then twisted causing the 95 resistance conductor to make two sharp bends over the edge of the hole 10, somewhat in an S-shape as shown in Fig. 3. The terminal is twisted several times causing the conductor to double on itself, until it 100 tightens by filling the groove and forcing against the core. The core is then placed in a winding machine, and the resistance conductor wound thereon a certain predetermined number of turns per inch which 105 allows sufficient space between the conductor for insulation. The conductor is then cut leaving sufficient to form an end

which is inserted in hole 7 of the core and hole 11 of terminal 5, whereupon the terminal 5 is twisted causing the end to tighten in similar manner as above described in the case of terminal 4. In this case however, such twisting also takes up any slack of the wire on the core. Mica washers 17 are now placed at the head of the core 1, the terminals projecting through the holes 18 and 19 therein. The threaded ring 20 is then placed over the washers. The unit thus formed is surrounded by the metallic sheath 14 which is slipped over the unit from the end opposite the terminal 15 projection and screwed to the ring 20. A filling cup is then secured to the opposite end of the sheath which holds the core central while it is being filled with a refractory insulating powder by means of a vibrator machine. After the sheath is so filled, the filling means are removed and the member 21 is screwed into place. The sheath is then compressed, preferably by swaging, which compresses the insulating material to a hard dense mass and fixes the turns of the resistance conductor to avoid any change in the relation of its parts due to the vibration of the machine on which it is used.

30 While I have described my invention as embodied in concrete form and as operating in a specific manner in accordance with the provisions of the patent statutes, it should be understood that I do not limit 35 my invention thereto, since various modifications thereof will suggest themselves to those skilled in the art without departing from the spirit of my invention, the scope of which is set forth in the annexed claims.

40 What I claim as new and desire to secure by Letters Patent of the United States, is:

1. An electric heating unit comprising a cylindrical core of insulating material, a metallic terminal inserted longitudinally thereof, and a resistance conductor wound on said core and having one end locked between the terminal and the core at a point within the core.

2. An electric heating unit comprising a cylindrical core of insulating material, a metallic terminal inserted longitudinally thereof, and a resistance conductor wound on said core and having one end wound on the terminal within the core so as to be held between the terminal and the core.

3. An electric heating unit comprising a cylindrical core of insulating material, metallic terminals inserted longitudinally thereof, and a resistance conductor wound on said core and having its ends wound on the terminals, respectively, within the core so as to be wedged between the terminals and the core.

4. An electric heating unit comprising a cylindrical core of insulating material, me-

tallic terminals inserted longitudinally thereof and having openings therethrough adjacent the end of the core, and a resistance conductor wound on said core and having its ends passing through the openings in 70 the terminals and wound thereon so as to be held tightly between the terminals and the core.

5. An electric heating unit comprising a core of homogenous insulating material, a 75 resistance conductor wound on said core, a metallic sheath surrounding the resistance conductor and core, and powdered heat refractory insulating material compacted to a hard dense mass within said sheath. 80

6. An electric heating unit comprising a solid cylindrical support of insulating material, a metallic terminal inserted longitudinally thereof, a resistance conductor wound on said support and connected to 85 the terminal, a metallic sheath surrounding the resistance conductor and support, and powdered heat refractory insulating material compacted to a hard dense mass within said sheath. 90

7. An electric heating unit comprising a solid cylindrical support of insulating material having longitudinal holes therein, metallic terminals inserted in said holes, a resistance conductor wound on said support 95 and connected to the terminals, a metallic sheath surrounding the resistance conductor and support, and powdered heat refractory insulating material compacted to a hard dense mass within said sheath. 100

8. An electric heating unit comprising a cylindrical core of insulating material, a metallic terminal inserted longitudinally thereof, a resistance conductor wound on said core and having one end wound on the 105 terminal within the core so as to be held between the terminal and the core, and a metallic sheath surrounding the resistance conductor and spaced therefrom by compacted powdered insulating material. 110

9. An electric heating unit comprising a cylindrical core of insulating material having longitudinal holes therein and transverse holes opening into the same, terminals inserted in said longitudinal holes having holes at right angles to said terminals coinciding with the transverse holes in the core, and a resistance conductor wound on said core and secured to the terminals through the holes therein by turning the 120 terminals.

10. An electric heating unit comprising a cylindrical core of insulating material having longitudinal holes therein and transverse holes opening into the same, terminals inserted in said longitudinal holes having holes therethrough coinciding with the transverse holes in the core, a resistance conductor wound on said core and secured to the terminals through the holes therein by 130

turning the terminals and a metal sheath surrounding the resistance conductor and in good thermal relation therewith.

11. An electric heating unit comprising a cylindrical core of insulating material having longitudinal holes therein and transverse holes opening into the same, terminals inserted in said longitudinal holes having holes therethrough coinciding with the 5 transverse holes in the core, and a resistance conductor wound on said core and having its ends passing through the holes in the terminals and wound on the terminals so as to be secured between the terminals and 10 the core.

12. A heating unit comprising a cylindrical core of insulating material having longitudinal holes drilled therein and transverse holes opening into the same, terminals 20 inserted in said longitudinal holes having holes therein, and grooves adjacent thereto, said holes and grooves coinciding with the transverse holes in the core, a resistance conductor wound on said core and secured 25 to the terminals through holes therein and around said grooves against the core, and a metal sheath surrounding the resistance conductor and in good thermal relation therewith.

30 13. The method of making an electric heating unit which consists in inserting a

metallic terminal longitudinally of a cylindrical insulating core, connecting a resistance conductor to the terminal at a point within the core, winding the resistance conductor upon the core and then tightening the resistance conductor by turning the terminal. 35

14. The method of making an electric heating unit which consists in inserting two metallic terminals longitudinally of a cylindrical insulating core, connecting a resistance conductor to one terminal at a point within the core, winding the resistance conductor upon the core, connecting the other 40 end of the conductor with the other terminal and then tightening the resistance conductor by turning the terminals.

15. The method of making an electric heating unit which consists in inserting 50 metallic terminals having a hole therein longitudinally of a cylindrical insulating core having a hole coinciding with the hole in the terminal, passing a resistance conductor through the holes in the core and 55 terminal, winding a resistance conductor upon the core and then tightening the resistance conductor by turning the terminal.

In witness whereof, I have hereunto set my hand this second day of May, 1919.

CHARLES C. ABBOTT.
